UNITED STATES PATENT OFFICE.

ADAM R. HENDRIX, OF CHICAGO, ILLINOIS, ASSIGNOR OF ONE-HALF TO W. H. BEALL,
OF CHICAGO, ILLINOIS.

VALVE MECHANISM FOR INTERNAL-COMBUSTION MOTORS.

1,187,620.

Specification of Letters Patent. Patented June 20, 1916.

Application filed April 24, 1912. Serial No. 692,790.

To all whom it may concern:

Be it known that I, ADAM R. HENDRIX, a citizen of the United States, residing at Chicago, in the county of Cook and State of Illinois, have invented certain new and useful Improvements in Valve Mechanism for Internal-Combustion Motors and the like, of which the following is a description.

My invention relates to the mechanism for controlling the entrance of fluid to, and its escape from the combustion chamber or cylinder of the motor.

The object of my invention is to provide a simple, convenient, durable and extremely accurate and reliable device of the kind described in which the moving parts are comparatively free from the influence of high temperature which might interfere with the operation of the device and is liable to cause distortion or deterioration of the parts.

To this end my invention consists in the novel construction, arrangement and combination of parts herein shown and described and more particularly pointed out in the claims.

In the accompanying drawings wherein like or similar reference characters indicate like or corresponding parts: Figure 1 is a transverse section taken substantially on line 1—1 of Fig. 2. Fig. 2 is a longitudinal section taken substantially on line 2—2 of Fig. 1. Fig. 3 is a sectional detail of the movable member and associated parts taken substantially on line 3—3 of Fig. 2. Fig. 4, 35 is a view similar to Fig. 2 but showing a slightly modified form of my device.

In the form of my device shown in the drawings 1 is the rear end of the cylinder or combustion chamber of an internal combustion engine having a head or cover 2 upon which my improved valve mechanism is mounted in any convenient manner. As shown a cylindrical casing 3 is formed upon the head 2 and provided with an inlet opening 4 and an outlet opening 5 through which the combustible is introduced to the cylinder and the spent gases are discharged. In the form shown the openings 4 and 5 are substantially opposite each other and connected to suitable pipes or tubes 6 and 7 for directing the fuel to, and the spent gases from, the device. A port 8 is provided in the casing substantially midway between the openings 4 and 5 and extends from the casing 3 to the interior of the cylinder. The

openings 4 and 5 and port 8 are preferably round or circular in section but may be of any form or size to suit the particular construction of the motor and are preferably arranged in line transversely of the casing 3 so that when the member or valve 9 which is positioned within the casing and formed to snugly fit the same is rotated, a transverse slot or opening 10 formed in the wall of the member will successively register with the openings and the port. The size and form of the slot is so proportioned that communication can never be opened directly between the openings 4 and 5, that is, the member 9 is so formed that one will always be closed before the other is opened; but a direct passage through the casing may be opened between the openings 4 or 5 as desired and the port 8. The several parts are so proportioned that when the member 9 is rotated in the direction indicated in the drawings the outlet opening 5 is first connected to the port 8 after which the opening 5 is closed and almost immediately the inlet opening 4 is connected to the port. The continued movement of the member 9 closes the port 8 when the member has completed approximately one-half of a rotation, and during the remainder of the rotation the openings 4 and 5 and port 8 remain closed; the periods of course accurately corresponding to the operating events of the motor.

In the preferred construction a recess 11 is formed in the casing 3 directly opposite the port 8 and extends longitudinally of the casing. An adjustable bearing block 12 is positioned in the recess with suitable screws 14 or other convenient means for adjusting the bearing block to the member 9 so as to hold the member firmly upon its seat and insure a suitable joint between the member and casing adjacent the port, and prevent the escape of any gases during the power stroke of the motor.

In the preferred form shown the casing 3 and member 9 are substantially the same length and a pair of plates or flanges 15 and 16 are attached to the ends of the casing with their central portion projecting inward beyond the walls of the member 9 thereby preventing longitudinal movement of the member in the casing but without interfering with the free circulation of air through the member which is preferably made tubular to avoid excessive heat and 110

consequent distortion. Any suitable means may be provided for rotating the member 9. In the form shown a bearing 17 is provided upon the flange 15 adapted to support a shaft 18 concentric with the member 9; a driver 19 is provided upon the shaft arranged to extend into a pair of notches or recesses 20-20 near the extremity of the member 9 so that when the shaft 18 is rotated the driver 19 will engage the walls of the notches 20 and rotate the member. In the preferred construction to avoid improperly engaging the driver 19 with the notches 20 I extend the shaft 18 into the member 9 sufficiently to insure the end of the shaft extending beyond the wall of the slot 10 or other convenient portion upon the interior of the member. The end of the shaft is cut away as at 40 or otherwise so formed that it will engage the part of the member 9 and prevent the engagement of the driver 19 with the slots 20 except when the parts are in the proper relation to each other.

In the form shown in Fig. 4 a pair of closures 25 are provided at the respective ends of the member 9 having projecting hubs 27 and 28 respectively each adapted to receive a hollow shaft or tube 29 and 30. The flanges 32 and 33 each operate as before described to prevent longitudinal movement of the member in the casing. In this form suitable means may be provided for directing a stream of water or other cooling medium through the shaft 29 into the interior of the member 9 whence it will escape through the shaft 30 thus cooling the member and controlling the temperature of the member as desired.

Having thus described my improvement it is obvious that various immaterial modifications may be made in my device without departing from the spirit of my invention, hence I do not wish to be understood as limiting myself to the exact form or construction shown.

What I claim as new and desire to secure by Letters Patent is:

1. In a device of the kind described, a casing having an inlet and an outlet opening and a port for connecting said casing to a cylinder, in combination with a rotatable member positioned within said casing and adapted when rotated to connect said port alternately to said openings during substantially one-half of each rotation, and to close said port and said openings during the remainder of its movement, an adjustable bearing block positioned substantially opposite said port and means for positively adjusting said block to control the position of said member, and means for rotating said member.

2. In a device of the kind described, a cas-

ing having an inlet and an outlet opening and a port positioned intermediate said openings for connecting said casing to a cylinder, in combination with a rotatable tubular member positioned within said casing and adapted when rotated to connect said port alternately to said openings, an adjustable bearing block positioned substantially opposite said port and means for positively adjusting said block to control the position of said member, means for rotating said member, and means for preventing the longitudinal movement of said rotatable member without closing the passage therethrough.

3. In a device of the kind described, a casing having an inlet and an outlet opening substantially opposite each other, a port positioned intermediate said openings for connecting said casing to a cylinder, in combination with a rotatable tubular member positioned within said casing and adapted when rotated to connect said port alternately to said openings, means for rotating said member, and means for preventing the longitudinal movement of said rotatable member and directing a fluid longitudinally therethrough.

4. In a device of the kind described, a casing having an inlet and an outlet opening substantially opposite each other, a port positioned intermediate said openings for connecting said casing to a cylinder, in combination with a rotatable tubular member positioned within said casing and adapted when rotated to connect said port alternately to said openings, an adjustable bearing block positioned substantially opposite said port and means for positively adjusting said block to control the position of said member, means for controlling the temperature of said member, and means for rotating said member.

5. In a device of the kind described, a casing having an inlet and an outlet opening and a port for connecting said casing to a cylinder, in combination with a rotatable member positioned within said casing and adapted when rotated to connect said port alternately to said openings, an adjustable bearing block mounted in said casing substantially opposite said port and means for positively adjusting said block to control the position of said member, means for controlling the temperatures of said member, and means for rotating said member.

In testimony whereof, I have hereunto signed my name in the presence of two subscribing witnesses.

ADAM R. HENDRIX.
